(57) **CLAIM**

The ornamental design for a diamond—121, shown and described in the drawings.

DESCRIPTION

FIG. 1 is a bottom plan view of a diamond showing my new design; and,

FIG. 2 is a side elevational view, it being understood that the broken lines are for illustrative purposes only and form no part of the claimed design.

1 Claim, 1 Drawing Sheet

FIG. 2

FIG. 1
